UNITED STATES PATENT OFFICE.

JOSEPH HIGHTON, OF MANCHESTER, ENGLAND.

LOOM-DOBBY.

SPECIFICATION forming part of Letters Patent No. 683,398, dated September 24, 1901.

Application filed March 5, 1901. Serial No. 49,850. (No model.)

To all whom it may concern:

Be it known that I, JOSEPH HIGHTON, weaving overseer, a subject of the King of Great Britain and Ireland, and a resident of 111 Gill 5 street, Blackley, Manchester, in the county of Lancaster, England, have invented certain new and useful Improvements in and Relating to Loom-Dobbies, (for which I have made application in Great Britain, No. 13,011, dated 10 July 19, 1900,) of which the following is a specification.

My said invention has reference to improvements in dobbies employed in looms for weaving for the purpose of lifting the healds for 15 shedding the warps, as is well understood.

The invention relates to an improved method of positively or directly actuating the hooks from the barrels, pattern-chains, or the like, so as to dispense with the use of feelers 20 or needles for raising such hooks.

The invention also relates to an improved form of bearing or connection for connecting or securing together the hooks and balks, such improved form of bearing or connection 25 being applicable for securing together the balks and "jacks," and it might be the jacks and healds.

My said invention will be clearly understood from the following detailed description, 30 throughout which reference will be made to the annexed three sheets of drawings.

In the said drawings, on Sheet 1, Figure 1 shows in side elevation my improved means for positively or directly actuating the hooks, 35 so much of a dobby-framing and working parts being indicated as is necessary for a clear understanding of my invention. Fig. 1^a is a separate view of one of the brackets which guide the barrels as they rise and fall. 40 On Sheet 2, Fig. 2 is an end elevation of Fig. 1 with certain of the parts broken away or omitted for the sake of clearness. Fig. 2^a shows a side view of the ordinary notched wheel and pawl used for rotating the barrel 45 or cylinder. On Sheet 3, Fig. 3 shows a side elevation of my improved connecting-balk, with attached hooks connected to the balk in accordance with my improvements. The figure also shows a jack-lever in connection 50 with a balk. Fig. 4 is an edge view of the balk. Fig. 5 is a vertical section of the bearing formed in the upper arm of the jack-le-

ver to receive the balk. Fig. 6 is an end view of one of the hooks. Fig. 7 shows one of the hooks in plan view.

55

Under the first part of my invention I employ the usual "griff-knives" for actuating the hooks; but these hooks are raised directly from the pattern barrels or cylinders, so as to dispense with the usual feelers or 60 needles.

In an arrangement for carrying my invention into effect and as clearly shown in Figs. 1 and 2 of the drawings I mount the barrels or cylinders *a a'* below the sets of hooks *b b'* 65 upon levers or links *c c*. These levers or links *c c* are jointed or connected by pivot studs *d d* to a pivoted lever *e*, centered at *e'*. It will be clearly understood that this arrangement of levers and links is duplicated, 70 so as to support the pattern barrels or cylinders at either end. (See Fig. 2.) In order to raise and lower the pattern-barrels *a a'* into and out of position for actuating the hooks *b b'*, I arrange to vibrate the pivoted levers *e*. This may be conveniently effected by means of an adjustable connecting-rod *f*, which is connected by swivel-joints *f' f'* to the pivoted levers *e* and to the compound lever *g*, pivoted at *g'*. This compound lever 75 is of the usual type and is operated in the usual manner from the cam or tappet shaft or the like of the loom. A suitable length of chain *h* is passed around chain-wheels *h' h'*, mounted on the axles of the pattern barrels 80 or cylinders, and in its course bears on each end of the pivoted lever *e*, which is provided with antifriction-bowls *h²*, upon which the chain rests, as clearly shown in the drawings. The vibration of the compound lever *g* actuates the connecting-rods *f*, so that these rods are in their turn pushed or pulled, and so rock each lever *e* on its center *e'*. The movement 85 of the levers *e* is communicated to the links *c c*, which sustain the pattern-barrel *a a'*. From 90 the above it will be seen that the movement of the levers *e* tends to alternately raise and lower the connected pattern barrels or cylinders *a a'*. At the time when the levers and links are cranked, as shown in full lines, Fig. 1, the upper pattern-barrel *a* is out of action while the lower pattern-barrel *a'* is in action. When the levers *e* and links *c* tend to assume a straight line, as shown in dotted lines,

Fig. 1, the upper pattern-barrel *a* is brought into action to operate the hooks *b* and the lower barrel is removed clear of the lower set of hooks. Upon the raising of either 5 pattern barrel or cylinder, due to the action of the ordinary compound levers *g*, the hooks are raised by the usual lags, chains, (indicated at *x*), or the like carried by the pattern barrel or cylinder and are operated in the 10 ordinary manner by the reciprocating griff-knives. To guide the pattern barrels or cylinders in their upward or downward movement, slotted or forked brackets *a*² may be employed. Fig. 1^a shows a separate view of such 15 a bracket. Fig. 1 shows the hook *b* as when raised ready for operation by the usual reciprocating griff-knife *k*. The hooks *b*¹ when worked by the knives *k* act on the connected balk *l* and "jack-levers" *m* and operate the 20 same to actuate the healds in the well-known manner. The barrels *a* *a*' are rotated by means of the usual notched or ratchet wheel *i*, worked by the pawl *i*' from the compound lever *g*. I have indicated this notched wheel 25 and pawl in Fig. 2^a. In the case of wide looms the jacks *m* in one set may be connected up to a second set of jacks by a connecting rod or tie, as indicated at *m*', Fig. 3. The healds may be pulled down by springs, 30 as is usual, or extensions from the jacks may be connected with a second set of jacks arranged below. By this latter arrangement better results are accomplished when working positively and dealing with heavy goods. 35 In order to obtain accurate working of the hooks, I propose to employ locking means to retain the hooks *b* *b*' in position and prevent unauthorized or premature movement of the same. To this end I employ a channeled or 40 other bar or bars *n*, extending across the dobby, the ends of the hooks when down dropping into such channel or against an adjustable cup *n*'. The said bar or bars *n* may be provided with an inclined face, upon which 45 the hooks rest when out of action. By these means any false movement of the balks is effectually prevented. To check backward movement of the balk, transverse bars *o* may be fitted across the dobby-framing. 50 In order to effect a ready and reliable connection between the hooks *b* *b*' and balks *l*, I provide the hooks with a trunnion *b*² and with two webs or fins *b*³ *b*³. Each end of the balk is suitably formed with a hole or bearing *l*² to receive the said trunnion *b*² and with 55 slots or ways *l*³ *l*³ for the webs or fins *b*³ *b*³, such slots or ways being so arranged as that in order to introduce the webs or fins it is necessary to turn the hook out of a working 60 position. The hook *b*' is shown as when out of a working position in Fig. 3, this part of the figure clearly showing the way in which the hook and balk are brought into connection with each other and the way the fins 65 engage the slots. When once the fins *b*³ *b*³ bear in the slots *l*³ *l*³ and the trunnion *b*² occupies its bearing *l*², the connection between

hook and balk is very effective and secure so long as the hook remains in a working position. A similar arrangement of fins and slots 70 or ways are preferably employed to connect the balks *l* to the ends of the jack-levers *m*, the fins *l*⁵ being formed on the balks and the slots *m*³ on the cranked arms of the jacks, a trunnion or bearing pin *l*⁴ being used to engage a bearing *m*² and secure an effective connection, as above described. This form of balk and jack-lever connection is clearly 75 shown in Fig. 3. If thought desirable, the healds may be connected up to the jacks by 80 means of a somewhat similar arrangement of fins and slots, as is indicated in Fig. 3, so that a slight turning is permissible as the jacks lift, and the healds are not strained or deflected. 85 By means of the bearing or connection above described the parts are readily strung together and when connected are well supported laterally. 90 My improvements simplify the dobby and render the same more perfect in working action. 95 When the loom is at work, the cam or tap-pet shaft raises and lowers the usual connecting-rod *A*, and so operates compound lever *g*. 100 As lever *g* is rocked it raises and lowers, through levers and links, the card-barrels *a* *a*', which are provided with the usual lags. As one or other barrel is brought into action the pins in lags operate where set to raise one or 105 other of the hooks in the sets *b* *b*'. When a pin or pins raise a hook or hooks, such hook or hooks is or are acted upon by the reciprocating griff-knife *k*. The griff-knives are 110 worked from the compound lever *g* by the rods *y*, dotted lines, Fig. 1. When the griff-knives act on the hook or set of hooks, the corresponding balks and connected jacks are affected so as to raise the healds or sets of 115 healds arranged in the looms. The raising 120 of the healds brings about the desired shedding of the warps, as will be understood. 125 I declare that what I claim is—

1. In combination in a loom-dobby, and as a means for positively or directly actuating the hooks so as to dispense with the use of 115 feelers or needles, the pattern cylinders or barrels *a*, *a*', links or levers *c*, *c*, supporting samie, pivoted levers *e* rocked from the usual compound levers *g*, said levers and links being surrounded by a chain *h*, said levers *e* being 120 operated to elevate or lower each pattern-barrel as required which in in turn work the hooks in the manner, for the purposes, and substantially as described.

2. In combination, in a loom-dobby in which the cylinders act directly on the hooks, the cylinders *a*, *a*', pivoted levers *e*, links *c*, and connecting-rod *f*, the connecting-rod *f* rocking the levers *e*, which in turn control the raising and lowering of the cylinders which operate the hooks, in the manner, and substantially as described.

3. In combination, in a loom-dobby, cylin-

ders a a' links c c and pivoted levers e , the levers e being actuated to raise and lower said cylinders which operate the sets of hooks b b' , griff-knives k for working hooks, and rests n , for said hooks when out of action, the combined parts acting, in the manner, and substantially as described.

4. In loom-dobbies the improved form of bearing or connection for securing or stringing together the hooks and balks, balks and jacks, &c., the bearing consisting of a part formed with a trunnion b^2 , l^4 and two fins b^3 ,

l^5 , the trunnions engaging circular apertures l^2 , m^2 , and the fins engaging curved recessed slots l^3 , m^3 , so that in a working position the parts are securely connected together, in the manner and substantially as described.

In witness whereof I have hereunto set my hand in presence of two witnesses.

JOSEPH HIGHTON.
